RECIPROCATING GRATER WITH
REMOVABLE TOOLPLATE

Theron H. Walker, Los Angeles, Calif.

Application March 3, 1945, Serial No. 580,745

4 Claims. (Cl. 146—178)

1

The invention relates to improvements in a grater or slicer for vegetables, fruits or the like.

An object of the invention is to provide a grater or slicer wherein the hand of the operator is not subjected to injury by the grating or slicing surface as would ordinarily be the case where the hand of the operator is employed to move the fruit or vegetable over the grater or slicer. According to the present invention, means are provided for advancing the food or the like to the grating or slicing tool without any likelihood of the hand of the operator coming in contact with the tool.

An object of the invention is to provide a tool of the class described wherein one hand of the operator may be employed to reciprocate the tool; the other hand being employed for advancing the material to the tool, the arrangement preferably being such that the pressure applied to advance the material to the tool serves also to hold the device on its support.

Another object of the invention is to provide an article of the class described with means permitting various graters or slicers to be interchanged.

Another object of the invention is to provide stop means for limiting the motion of the tool in opposite directions, wherein the stop means are removable to permit the tool to be removed from the device for cleansing purpose, or otherwise.

Another object of the invention is to provide a device of the character described wherein a handle on a pusher for advancing the material through a hopper to the tool is movable towards the reciprocating path of the tool whereby the two hands of the operator are, generally speaking, compressed together while one of them is reciprocating the tool, and the other is advancing the material to the tool.

For further details of the invention, reference may be made to the drawings, wherein:

Figure 1 is a perspective view of a grater or slicer according to the present invention.

Fig. 2 is a plan view of the tool holder or frame and tool plate of Fig. 1.

Fig. 3 is an enlarged sectional view, with parts broken away, on line 3—3 of Fig. 2.

Fig. 4 is a vertical sectional view of the device of Fig. 1.

Fig. 5 is a rear view in elevation of the device in Figs. 1 and 4 looking in the direction of the line 5—5 at the right of Fig. 4, and with the tool frame and pusher in depressed positions.

Fig. 6 is a sectional view on line 6—6 of Fig. 5.

2

Figs. 7 and 8 are plan views of different forms of tool plates which may be employed in the device of the other figures.

Fig. 9 is a sectional view on line 9—9 of Fig. 10, the latter showing an enlarged plan view with parts broken away of the releasable stop appearing at the lower right-hand corner of the tool frame in Figs. 1 and 2.

Referring in detail to the drawings, the grater or slicer 1 of this invention comprises a tool frame 2 to which is removably secured a desired tool plate 3, the frame 2 having a handle 4 by means of which it can be reciprocated on a guide plate or hopper 5 across the open end of a hopper 6. The vegetable or fruit or the like to be sliced or grated is placed in the hopper 6 and the handle 7 is pushed downwardly to swing the pusher 8 and advance the food in the hopper 6 against the tool plate 3.

All of the parts of the device 1 are preferably made of sheet metal such as sheet iron stampings coated with tin. The frame 2 is, likewise, preferably made of sheet metal and provided with in-turned flanges 9 and 10 on its opposite edges, to engage and ride on the upturned flanges 11 and 12 on plate 5, the flanges 11 and 12 serving as rails.

The upper portion of the frame 2 is preferably not cut away in order to provide strength and to this imperforate portion 13 is riveted or otherwise secured the handle 4, the upper end 14 of which is preferably bent across the top of the frame 2 in order to serve as a stop and engage the rubber bumper 15 (see Fig. 4) suitably secured to the upper end of the plate 5.

The lower part of the frame 2 is cut away to provide a rectangular opening 16 over which the tool plate 3 fits from the rear of plate 2 so that pressure applied to the material in hopper 6 by the pusher 8 serves to hold the removable tool plate 16 in position on frame 2. The length and breadth of the tool plate 3 are slightly larger than the corresponding dimensions of the rectangular opening 16 and the lateral edges 17 and 18 of the tool plate 3 are shown as overlying the side edges 19 and 20, respectively, of the frame 2, in Fig. 6.

In order to provide for removability of the tool plate 3, the bottom of the frame 2 is provided with one or more inwardly and downwardly projecting lugs, two being illustrated at 21 and 22, stamped out from the sheet metal of frame 2. One of these lugs 21 is shown at the bottom of Fig. 3, and it is adapted to be engaged by an aperture 23 in the lower end of the tool plate 3, the upper end of tool

plate 3 having an integral spring roll edge 24 adapted to project through and resiliently engage by friction the lower edge 25 of an aperture 26 stamped out of an intermediate portion of the frame 2. The lugs 21, 22 hold the lower end of the tool plate 3 against the rear face of the frame 2. Lugs 21, 22 also resist the spring tension in the spring roll 24. If the lower end of handle 4 projects below the lower edge 24 as indicated in Fig. 1, the slot 26 preferably should not extend behind the lower end of handle 4 and the roll edge 24 is intercepted by the lower end of handle 4; that is, the slot 26 is, in effect, two aligned slots, the other one being 27, and the roll edge 24 is, in fact, two aligned roll edges, the other being shown at 28, with the material of frame 2 behind the lower end of handle 4 imperforate for rigidity.

Motion of the tool frame 2 in an upwardly direction is releasably limited by a vertically-extending lug 29 struck out of the plate 5 at the side thereof, as indicated in Figs. 1 and 9, and cooperating therewith is a pivoted catch 30 having an inturned lug 31 which passes through a slot 32 in the frame 2, the slot 32 permitting the pivoted lug 31 to be moved by handle 33 to the position shown in Fig. 9, where the lug 31 extends across and under the lug 29 to limit the upward movement of the tool frame 2. The slot 32 also permits the catch 30 to be rotated about 90° to a position where lug 31 is parallel to and at one side of the lug 29 as shown at the left side of Fig. 6, whereby when the catch 30 is in that position, as shown in Fig. 1, the plate 2 may be moved vertically until it is removed from the rails 11 and 12. This may be done to clean the parts of the device or to change the tool plate 3.

As indicated in Fig. 1, one form of tool plate 3 is provided with a series of downwardly directed and rearwardly projecting knives 34. A different form of tool plate 35 having a different arrangement of downwardly directed knives 36 as indicated in Fig. 7. A still different form of tool plate 37 having one or more downwardly directed knives 38 each of which may angularly extend almost the full width of the tool plate, is shown in Fig. 8. The tool plate 35 has apertures 39 at its lower end and a spring roll 40 at its upper end like that previously described for tool plate 3, and the same is true of all the other tool plates so that they are interchangeable to fit the lugs 21 and 22, and apertures 26 and 27.

The hopper 6 laterally or rearwardly projects from the plate 5 with the end 41 of the hopper 6 terminating at the plate 5. The plate 5 has a hole 42 stamped out of it, somewhat in the shape of a sector of a circle. This is shown partly in Fig. 1, and also in Fig. 5. The hopper 6 is somewhat V in shape and it conforms to the V-shape of the sides and bottom of the aperture 42, and the hopper 6 is secured therein by having integral lugs 43, shown in Figs. 1 and 5, which extend across the front edge of the aperture 42 and are inserted through apertures like 44 and bent over at the rear of the plate 5.

The lower end of plate 5 has a transverse flange 45 serving as a foot to rest on a horizontal support, and a companion foot piece 46 is formed of a sheet metal bracket 47 which is secured to the outer end of hopper 6, as indicated at 48.

As shown in Fig. 4, the pusher 8 is provided with teeth 49 which may be struck out from the sheet metal body of the pusher 8, to prevent the fruit or vegetable, as indicated at 50 in Fig. 4, from turning when it is advanced to and operated on by the tool plate 3. The contour of the

pusher 8 is somewhat V-shaped as indicated in Fig. 5, to conform substantially to the contour of the hopper 6.

As shown in Figs. 1 and 4, the pusher handle 7 is somewhat in the shape of a D, the vertical branch of which is riveted to the pusher plate 8, as indicated at 51, the horizontal branch 52 of which extends parallel to the bottom of the hopper 6 when the pusher 8 is in its innermost position, shown in dotted lines at 53 in Fig. 4, where the ends of the metal strip forming the handle 7, as indicated at 54 in Fig. 4, serve as a stop and strike the outer end of the hopper 6.

The pusher 8 is pivoted on a transverse axis on hinge 55, at the rear of the upper end of plate 5, as indicated in Figs. 4 and 5. The flange 45 which forms a foot is arranged preferably at one side of a vertical through the hinge 55, and with the foot piece 46 arranged on the other side of that vertical, whereby downward pressure on hinge 55 applied by handle 7, serves to hold the device on its support, not shown. The transverse hinge 55 also provides an arrangement where the two hands of the operator are, generally speaking, moved towards each other in operating the device, as the arc of feeding movement of the pusher 8 is in a direction toward the line of movement of the handle 4. This operation is facilitated by arranging the handle 4 on the tool plate 2 and the handle 9 on the pusher 8 on the outer surfaces thereof, opposite to their adjoining surfaces. Referring to Fig. 4, if a vertical is dropped from hinge 55, it will be seen that the bottom of the hopper 6 extends on opposite sides of this vertical, its outer end being more remote from the vertical than its inner end which merges with the opening 42 in the slide supporting plate; also this vertical intersects the angle formed by the inclined slide support 5 and the pusher 8 when the latter is partially open. This makes the device stable on a support, as the downward force is acting on the handles 4 and 7 which lie substantially within the base of the feet 45 and 46.

Preferably the flange 45 and foot piece 46 serve to support the plate 5 with its rails 11 and 12 and the frame with its tool plate 3 in an inclined upright position, as shown in Figs. 1 and 4, so that the grater or slicer and its action can be readily inspected.

Various modifications may be made in the invention without departing from the spirit of the following claims.

I claim:

1. A comminuting tool slide having an opening and means removably securing a tool plate over said opening, said means comprising a spring roll on one end of said plate and said slide having a cooperating aperture for said spring roll above said opening, also downwardly projecting lug means on said slide below said opening and cooperating aperture means at the other end of said tool plate, said lug means serving to hold said tool plate against one side of said slide and hold said spring roll in frictional engagement with its said aperture with said spring roll projecting therethrough to the other side of said slide.

2. A comminuting utensil comprising an inclined slide support having a hopper thereon, a tool plate holder slidable on said support, a handle on said holder, a pusher for said hopper, said pusher having a hinge connection with said support above said hopper, said hopper having a bottom extending on opposite sides of a vertical through said hinge, a handle on said pusher, said slide support and said hopper having a foot rest

extending on opposite sides of a vertical line through said hinge, and said slide support supporting said holder for sliding movement on one side of said vertical and said hinge supporting said pusher handle for swinging movement on other side of said vertical whereby downward pressure on said slide holder handle and downward pressure on said pusher handle serve to steady said slide support and hopper on said foot rest.

3. A comminuting utensil according to claim 2 wherein said hopper has an outer end at some distance from one side of said vertical and an inner end merging with an opening in said slide support at a less distance from and on the other side of said vertical.

4. A comminuting utensil according to claim 2 wherein said slide support is inclined downwardly

5

and outwardly, the angle formed by said inclined slide support with said pusher when partially open being intersected by a vertical through said hinge.
